UNITED STATES PATENT OFFICE.

ARTHUR E. SIMPSON, OF WEST FRANKFORT, ILLINOIS, ASSIGNOR OF ONE-SEVENTH TO H. L. WEBB, ONE-SEVENTH TO J. M. HARRIS, ONE-SEVENTH TO B. H. WEBB, ONE-SEVENTH TO T. M. SILKWOOD, ONE-SEVENTH TO R. P. BLAKE, AND ONE-SEVENTH TO C. E. PITCHFORD, ALL OF WEST FRANKFORT, ILLINOIS.

ROTARY PUMP.

Application filed June 2, 1924. Serial No. 717,307.

My invention relates to improvements in rotary pumps and has for its primary object a rotary pump which will deliver a maximum amount of liquid with a minimum amount of power and in which pulsations of delivery are practically eliminated.

A further object is to construct a rotary pump which can be run either right or left hand by merely removing and reversing the rotor.

A still further object is to construct a rotary pump in which the pistons are not dependent on centrifugal force or mechanical movement to hold them against the cylinder, but in which the suction and the fluid pump have a tendency to cause the pistons to move outwardly and fit tightly against the cylinder.

In the drawings:

Fig. 1 is a side elevation of my device with the driving means removed;

Fig. 2 is a top plan view of the same;

Fig. 3 is a vertical cross section taken on the line 3—3 of Fig. 2;

Fig. 4 is a horizontal cross section taken on the line 4—4 of Fig. 1 with the rotor removed;

Fig. 5 is a top plan view of one of the pistons;

Fig. 6 is a bottom plan view of the same;

Fig. 7 is an enlarged view of the rotor looking at the same in the direction of the arrow A of Fig. 11;

Fig. 8 is an enlarged view of the rotor looking at the same in the direction of the arrow B of Fig. 11;

Fig. 9 is an enlarged fragmental section of the rotor and piston as viewed from the top with the piston in closed position and illustrating the passages;

Fig. 10 is an enlarged fragmental section of the rotor and piston showing the passages on the underside of the piston;

Fig. 11 is an end elevation of the rotor with the pistons removed; and

Fig. 12 is an end elevation of the pump and driving mechanism when assembled ready for operation.

In the construction of my device I employ a housing 13 which comprises a base 14, and a cylinder 15. Formed in the base 14

are openings 16 and 17 which are screw threaded to receive pipes 18 and 19, and which are the delivery and suction pipes respectively. The screw threaded opening 17 opens into a chamber 20, which will hereafter be termed the suction chamber, while the screw threaded opening 18 opens into a chamber 21, which will hereafter be termed the delivery chamber. The chamber 20 has extending therefrom and into the cylinder 15 a plurality of openings or ports 22. These openings or ports are preferably elongated and are of such size that their combined areas will equal the area of the pipe 19. While the chamber 21 communicates with the cylinder 15 by means of similar openings or ports 23 which are similarly constructed. Between the chambers 21 and 20 is an abutment wall 24.

The housing 13 is provided with screw threaded openings 25 into which cap screws 26 fit. These cap screws are for the purpose of securing the heads 27 to the opposite sides of the housing, a leak proof joint between the heads and housing being accomplished by means of packing 28. The heads are also provided with a gland 29 through which a shaft 30 extends. The gland 29 however, is so positioned on each head as to be eccentric to the bore of the cylinder 15, so that the rotor 31 which is secured to the shaft 30 will fit closely against the abutment 24. This is necessary in order to divide the cylinder into a suction and a delivery chamber. The cylinder 15 is further provided on its interior face with arcuate recesses 32 and 33, these recesses commencing at the openings 22 and 23 respectively, and gradually decreasing in depth as they extend from the respective openings. This is clearly illustrated in Fig. 3 and the purpose thereof will be described in detail later.

The rotor 31 is also provided with cut-away portions 35 and with sockets 36. These cut-away portions and sockets permit the insertion of pistons 37. The pistons 37 are provided with cylindrical projections 38 which are adapted to slide into the sockets 36 so that the pistons will be hingedly mounted. These pistons are substantially triangular in section, as illustrated in Fig. 3,

and have their outer surfaces 39 arranged so as to form a continuation of the surface of the rotor 31. A portion of the outer surface 39 is provided with depressions 40 which are rectangular in shape so as to form diagonally extending ribs 41. These depressions are filled with a bearing metal 42 which is preferably softer than the material out of which the housing 13 and the pistons 37 are formed, and if not softer, at least of a different metal so that friction is reduced. It is a well known fact in physics that two like metals running on each other create more friction than unlike metals. Where a softer filling is used the ribs 41 prevent rapid wear and by their diagonal distribution prevent cutting of ridges within the cylinder.

The edge 43 of the pistons 37 acts as a pushing edge and is provided with V shaped grooves 44, which grooves are in alinement with grooves 45 cut in the edge 46 of the recesses 35. The underneath face 47 of the pistons 37 is likewise provided with V shaped grooves 48 which are in alinement with similar grooves 49 cut in the face 50 of the recesses 35. The grooves 45 and 49 and 44 and 48 are continuous so that any fluid which passes into the grooves 44 and 45 will also pass into the grooves 48 and 49. The purpose of this will be explained in detail later.

Secured to each gland 29 is a packing nut 51 by means of which the shaft 30 is so packed as to prevent any leakage. The heads 27 are provided with packing rings 52 which are adjusted by means of screws 53 and are for the purpose of preventing leakage between the cylinder heads and the rotor.

The pump is preferably mounted on a table 54 which is supported by legs 55, these legs in turn supporting the motor or other source of power 56. Secured to the shaft 30 is a pulley 57, while the motor carries a pulley 58, and around these two pulleys passes a belt 59. The belt is given its proper tension by means of an idler 60 which is carried by the table 54 and which is preferably controlled by means of a counterweight 61, although if desired, a spring tension for the idler may be used, the sole purpose of the idler being to keep the belt sufficiently tight to operate the pump and take care of any stretch in the belt.

I may however, if desired, connect my pump directly to the source of power or use gearing or other well known means to drive the pump without departing from the spirit of my invention.

It will be noted from Figs. 3 and 4 that the openings 22 and 23 and the recesses 32 and 33 are spaced apart so as to leave ridges or ribs in between. These ridges or ribs form a continuation of the bore of the cyl-

inder 15 so that the pistons 37 will have a continuous circular support throughout their rotation.

The operation of my device is as follows:—

After the pump is assembled and connected up, the rotor is rotated in the direction of the arrow in Fig. 3. In this connection it is essential to note that the only point of contact between the rotor and the cylinder is the abutment 24. As soon as the piston passes the abutment 24 it drops downward by gravity and as it continues to rotate follows the bore of the cylinder and gradually moves away from the center of rotation or out of the rotor.

The piston fitting snugly against the wall of the cylinder creates a suction behind it which draws the fluid to be pumped into the chamber 20 and from there through the openings 22 into the cylinder. This suction also tends to hold the piston against the cylinder wall, or in other words prevents gravity from causing the piston to drop backward into the pocket or recess 35. As soon as the next piston passes the abutment, this operation is repeated with the addition that some of the fluid thus trapped between the two pistons enters the passage ways formed by the grooves 44 and 45 and 48 and 49. The fluid thus entering fills up the space between the piston and the bottom of the recess 35, and further assists in holding the piston tightly against the periphery of the cylinder. As soon as the piston has passed the point on the periphery of the cylinder directly opposite the abutment 24, it is gradually forced into the pocket. This is due to the eccentric mounting of the rotor and as the piston is thus forced in, any fluid which is in the space between the bottom of the recess 35 and the face 47 of the piston is forced out through the passage way assuming a reversed direction from that in which it enters.

It is very essential that provision be made to permit the fluid to escape readily as otherwise there would be a possibility of trapping some of the fluid and cause it to form a cushion which would prevent the entire collapse of the piston into the rotor and set up a great amount of useless friction.

By the peculiar construction of the outlet and intake, and especially the location of the grooves 32 and 33 it is possible to have both pistons delivering fluid at the same time. In fact as soon as the delivery face 43 of one piston commences to ride on the ridges formed between the openings 23, communication is established with the liquid which is being pushed by the other piston. This permits a slight amount of fluid to pass into the groove 33 and as this amount increases it also has a tendency to force the piston nearest the discharge opening 23 into

the pocket, thus relieving friction to a great extent. And after one piston has passed the abutment it will continue to have a sucking action until the succeeding piston has reached a point past the ribs or ridges between the groove 32. By this construction there are no sudden pulsations either of suction or delivery because by the arrangement of the grooves the suction and delivery of each piston is overlapped by the suction and delivery of the other.

I have also discovered that by utilizing the grooves 32 and 33 that the capacity of the pump can be practically doubled, as well as permitting the pump to be run with less power.

My pump can be readily reversed in action, that is, the suction and delivery directions of the pump can be readily changed by merely removing the rotor and reversing its position in the housing and rotate it in the opposite direction to that shown in Fig. 3, because there are no check valves used in this pump, as is the case in reciprocating pumps.

It will further be noted from Fig. 3 that the end 43 of the pistons 37 presents a flat face which extends substantially radial to the cylinder when in contact against the cylinder wall, thus the fluid being pumped has the tendency to hold the piston against the cylinder. This tendency of the fluid is assisted by the relatively large spaces between the surfaces 43 and 46 thus readily permitting the passage of fluid into the space as the piston swings out from the rotor, and also allowing its ready ejection when the piston is collapsed into the rotor, which collapse is caused by the eccentric mounting of the rotor in the cylinder.

Having fully described my invention, what I claim is:—

1. A rotary pump comprising a housing having a base, a cylinder formed in said housing above said base, a rotor eccentrically mounted in said cylinder, a pair of substantially triangular pistons pivotally mounted at their rear ends and diametrically opposite each other in said rotor and adapted to contact with the periphery of said cylinder, a plurality of intersecting ribs formed on the outer face of said pistons, bearing metal located between said ribs, a suction chamber formed in said base, a delivery chamber formed in said base, a plurality of laterally spaced parallel passages gradually increasing in depth and having ports therein at their point of greatest depth for connecting the suction and delivery

chambers with the interior of the cylinder, and an abutment located between said ports and said passages and the chambers in the base, said abutment being in constant contact with the rotor.

2. A rotary pump comprising a housing having a base, a cylinder formed in said housing above said base, a cylindrical rotor eccentrically mounted in said cylinder, a pair of substantially triangular pistons pivotally mounted at their rear ends in said rotor and adapted to contact with the periphery of said cylinder, a suction chamber formed in said base, a delivery chamber formed in said base, a plurality of laterally spaced parallel passages gradually increasing in depth and having ports therein at their point of greatest depth for connecting the suction and delivery chambers with the interior of the cylinder, means formed in the rotor and piston for permitting some of the fluid being pumped to forcibly pass to the underside of said pistons for holding the same against the periphery of the cylinder, and an abutment integral with said housing and located between said ports and chambers, said abutment being in constant contact with the rotor.

3. A rotary pump comprising a housing having a base, a cylindrical bore formed in said housing, heads located on opposite sides of said housing for closing said bore, a rotor having diametrically opposite, substantially triangular recesses extending across its periphery eccentrically and rotatably mounted in said casing, pistons substantially triangular in longitudinal section pivotally mounted at their reduced ends in said recesses, passageways formed in two faces of said recesses and in the adjacent faces of said pistons for permitting fluid being pumped to freely pass to and from the underside of said pistons, a suction chamber formed in the base, a delivery chamber formed in the base, an abutment between said chamber and terminating flush with the cylindrical bore, a plurality of spaced channels gradually decreasing in depth formed in said bore and extending at right angles to said abutment and in opposite directions therefrom, said channels extending only partly around said bore, and ports formed in said channels at their point of greatest depth and communicating with the suction and delivery chambers for permitting liquid to pass therethrough to and from the cylindrical bore.

In testimony whereof, I have signed my name to this specification.

ARTHUR E. SIMPSON.
